UNITED STATES PATENT OFFICE.

WELLINGTON PARKER KIDDER, OF BOSTON, MASSACHUSETTS, ASSIGNOR TO PARKER MACHINE COMPANY, OF BUFFALO, NEW YORK, A CORPORATION OF NEW YORK.

CARRIAGE-SHIFTING MECHANISM FOR TYPE-WRITERS.

No. 882,828.

Specification of Letters Patent. Patented March 24, 1908.

Application filed June 24, 1905. Serial No. 286,812.

To all whom it may concern:

Be it known that I, WELLINGTON P. KIDDER, residing at Boston, in the county of Suffolk and State of Massachusetts, have invented certain new and useful Improvements in Carriage-Shifting Mechanism for Type-Writers, of which the following is a full, clear, and exact description, such as will enable others skilled in the art to which it 10 appertains to make and use the same.

This invention relates to typewriting machines and the like and, although capable of use in many forms of machines, is especially adapted for use in machines known as "silent" typewriters, and has for one of its objects the provision of means whereby a machine of the above type will operate without noise.

A further object is to provide mechanism 20 adapted to shift the carriage silently from initial position to other positions.

Other objects will be in part obvious and in part pointed out hereinafter.

The invention accordingly consists in the 25 features of construction, combinations of elements and arrangement of parts which will be exemplified in the mechanism hereinafter described and the scope of the application of which will be indicated in the 30 following claims.

In the accompanying drawings, wherein is illustrated one of several possible embodiments of my invention, Figure 1 is an end elevation of the same, partly in section. 35 Fig. 2 is a plan view of a portion of the same. Fig. 3 is an elevation, partly in section, showing the parts illustrated in Fig. 2. Fig. 4 is a view of a detail.

Similar reference characters refer to similar parts throughout the several views.

As tending to render clearer certain of the various general features of my invention, it may here be noted that, in typewriters wherein a small number of keys are employed, 45 requiring the arrangement of the printing devices in groups, it is necessary to provide mechanism adapted to shift the same to several positions in order to employ a printing character from any one of the several 50 groups. I have, therefore, found it desirable in machines of the above type to provide means whereby the carriage may be shifted silently from initial position to other positions. The above and other advan-

tages are secured in constructions of the 55 nature of that hereinafter described.

Referring now to the drawings, a vertically reciprocating carriage 1 has secured thereto a channel bar 2 in which is slidably mounted a block 3. Double rocker arm 4 pivoted at 60 5 to bracket 6 carried by the frame of the machine is pivotally attached at one end to block 3 and at its opposite end to piston rod 7 which is adapted to carry piston 8 working in dashpot 9. When the carriage 1 is in 65 initial position, as shown in the drawings, piston 8 is in engagement with the bottom wall of dashpot 9. Piston rod 7 comprises a lower member 10 fixedly mounted in piston 8 and has its upper end split and internally 70 threaded to engage with member 11 and externally threaded to carry lock nut 12. Members 10 and 11 are therefore capable of adjustment in order to shorten or lengthen piston rod 7, thereby operating to determine 75 the position of the carriage 1 when piston 8 is in engagement with the bottom wall of dashpot 9, as hereinbefore explained, lock nut 12 operating to maintain members 10 and 11 in fixed adjustment.

To the opposite end of rocker lever 4 there is pivotally attached at 13 an adjustable piston rod 14 constructed similarly to piston rod 7 above described, which carries at its lower end piston 15 operating in dashpot 16. 85 Dashpot 16 is carried by an arm 17, pivoted to bracket 6 and carries a cam roller 18 journaled thereon at 19 adapted normally to rest on a sliding cam 20, as clearly shown in Fig. 3 of the drawings. Sliding cam 20 resting on guide roller 21 journaled to a stud 22 positioned upon the frame of the machine, extends between flange 23 and stud 22 and is adapted to be reciprocated endwise by shift lever 24 journaled on key lever shaft 25 95 acting through link 26 pivotally connected at one end to arm 27 of shift lever 24 and at its opposite end to bell crank lever 28 pivoted to the frame of the machine at 29 and to which sliding cam 20 is pivotally attached at 30. Link 31 is pivotally connected at one end to double rocker lever 4 at 32 and at its opposite end to lever 33 positioned upon rock shaft 34. Forked lever 35 is carried upon rock shaft 34 and is 100 adapted to be actuated by arm 36 carried by movable abutment 37 fixedly positioned upon key lever shaft 25 journaled in the

frame of the machine. Arm 36 is provided with a ball 38 engaging between the members 39 and 40 of forked lever 35, thereby constituting a universal connection there-
5 with.

Shift lever 41 which in the present instance may be designated as the "Cap" lever, is journaled on key lever shaft 25 and is provided with a shoulder which is
10 adapted to engage with movable abutment 37 at 42 and actuate the same to cause a movement of rock shaft 34 through the universal connection therewith, such movement being communicated through arm 33
15 and link 31 to double rocker arm 4, to shift the carriage 1 and cause piston 15 to be projected downwardly in dash pot 16, the imprisoned air therein forming a cushion, thereby yieldingly resisting such move-
20 ment and causing piston 15 to silently impinge against the bottom wall of dash pot 16. When the platen occupies this position, the carriage is in its second or "Cap" position and, by reason of piston rod 14 be-
25 ing adjustable, the location of the carriage with respect to the printing characters can be accurately determined, inasmuch as the bottom wall of dash pot 16 operates as a stop to always arrest the movement of the
30 carriage in the same position. Upon the releasing of the pressure on the shift lever 41, spring 43 forces carriage 1 to initial position, this operation being assisted by re-
tractile spring 44 interposed between link 31
35 and the frame of the machine at 45 and re-
tractile spring 46 secured to arm 47 positioned upon rock shaft 34 and adjusting screw 48 extending from the frame.

Shift lever 24 in the present instance be-
40 ing designated as "Fig." key, is adapted upon the application of pressure thereon to engage with movable abutment 37 and through the connections with the carriage 1, as hereinbefore explained with reference
45 to shift lever 41, to cause a movement there-
of, and simultaneously with this movement, arm 27 of shift lever 24 by means of link 26 and bell crank lever 28 operates to slide cam 20 allowing cam roller 18 of dash pot 16 to
50 travel along cam face 49 of said sliding cam 20, thereby permitting dash pot 16 to swing on its pivot to assume a lower position, the motion being arrested upon the engaging of
55 cam roller 18 with the horizontal surface of sliding cam 20. At this instant piston 15 is approaching the bottom of dash pot 16, the imprisoned air therein operating to cushion the arresting of movement thereof by the bottom of said dash pot. It will be
60 seen that the carriage 1 has thus been shifted to a third position. During this operation the piston 8 connected to double rocker arm 4 has been carried upward in dashpot 9 and upon a releasing of pressure on shift lever 24,
65 the upward movement of the carriage by

the actuating means above described will cause piston 8 to engage with the bottom wall of dashpot 9, the imprisoned air therein operating to silently arrest such movement.

Although it will be apparent that I may 70 perforate the piston or employ any suitable means whereby the imprisoned air may es-
cape, I have, in the present instance, con-
structed the pistons 8 and 15 to fit loosely in
their respective dashpots in order that the 75 said imprisoned air may slowly escape during
the operation of arresting the movement of
the carriage in either direction, thereby al-
lowing said pistons to engage the bottom
walls of dashpots 9 and 16, respectively, such 80 engagement, as hereinbefore described, deter-
mining the position of the carriage with re-
spect to the printing devices carried by the
type bars.

Shift key lock 50 is pivotally mounted 85 upon stud 51 extending from the frame of the machine and is provided with a cam face 52 adapted when said lock is swung on its pivot 51 to engage either of spurs 53 or 54 of shift
levers 24 and 41, respectively, to maintain 90 either lever in its downward position, thereby holding the carriage 1 in either of its shifted positions.

While I have, in the present case, described 95 shift lever 41 as the "Cap" lever and shift lever 24 as the "Fig." lever, it is obvious that this arrangement is merely arbitrary and such arrangement may be reversed. It will be also understood that while I preferably employ a vertically reciprocating carriage 100 with my shifting devices, the same may be adapted with equal efficiency to a different arrangement, in which the carriage is fixed against vertical movement, the several groups of printing devices comprising the 105 type basket being arranged to reciprocate vertically.

The operation of my invention, which should be largely obvious from the above de-
scription is substantially as follows: Pres- 110 sure on shift lever 41 will, through the con-
necting means hereinbefore specifically de-
scribed, cause a movement of the carriage
from initial position to the second position,
and the movement thereof will be arrested 115 by the air cushion operating upon piston 15. When, however, pressure is applied to shift
lever 24, the above operation is repeated and simultaneously therewith link 26 connected to
shift lever 24 causes sliding cam 20 through the 120 operation of bell crank lever 28, to be with-
drawn from under dashpot 16, allowing the
same to assume a lower position, and conse-
quently permitting a further movement of
the carriage, the air cushion, as before, cush- 125 ioning the descent thereof. The air-cushion
of dashpot 9 operates to silently arrest the
return of the carriage to initial position from
either of its shifted positions.

It will thus be seen that I have devised a 130

carriage shifting mechanism wherein the objects of my invention are attained, characterized by simplicity and efficiency and one in which concussion or impact of moving parts has been to a great extent eliminated, and wherever parts are brought into contact one with another the production of noise is prevented by the employment of a cushion.

While I have shown and described my invention in connection with a typewriting machine of the above type, I do not wish to be understood as limiting myself exclusively to that type alone, as it is adapted as to many of its features to other types of machines, 15 although of peculiar value in the relation shown.

As many changes could be made in the above construction and many apparently widely different embodiments of my invention could be made without departing from the scope thereof, I intend that all matter contained in the above description or shown in the accompanying drawings shall be interpreted as illustrative and not in a limiting 25 sense. I desire it also to be understood that the language used in the following claims is intended to cover all of the generic and specific features of the invention herein-described and all statements of the scope of the invention, which as a matter of language, might be 30 said to fall therebetween.

Having described my invention, what I claim as new and desire to secure by Letters Patent, is:—

35 1. In a typewriting machine, in combination, a carriage, means for shifting the carriage from initial position to a second position, movable means adapted to arrest the movement of the carriage in such position, 40 said first-mentioned means being adapted to shift the carriage to a third position upon a movement of said movable arresting means, and means adapted to arrest the movement of said arresting means when the carriage 45 has reached the third position.

2. In a typewriting machine, in combination, a carriage, means adapted to shift the carriage from initial position to a second position, a shift lever for actuating said 50 means, movable means adapted to arrest the movement of said carriage when such position is reached, a second shift lever adapted to 55 actuate said first-mentioned means to shift said carriage to a third position upon a movement of said arresting means, and means actuated by said second-mentioned shift lever adapted to allow a movement of said arresting means.

3. In a typewriting machine, in combination, a carriage, means adapted to shift the carriage from initial position to a second position, a shift lever for actuating said 60 means, movable means adapted to arrest the movement of said carriage when such position is reached, a second shift lever adapted

to actuate said first-mentioned means to shift said carriage to a third position upon a movement of said arresting means, and means actuated by said second shift lever adapted to permit a movement of said arresting means, said last-mentioned means operating to arrest the movement of said carriage in said third position.

4. In a typewriting machine, in combination, a carriage, means for shifting the carriage from initial position to a second position, and means pivoted to the frame of the machine adapted to arrest the movement of the carriage in such position, said first-mentioned means being adapted to shift the carriage to a third position upon a movement of said pivoted arresting means in the direction of the movement of the carriage.

5. In a typewriting machine, in combination, a carriage, means adapted to shift the carriage from initial position to a second position, a shift lever for actuating said means, means pivoted to the frame of the machine adapted to arrest the movement of said carriage when such position is reached, 85 and a second shift lever adapted to actuate said first-named means to shift said carriage to a third position upon a movement of said arresting means in the direction of the movement of the carriage.

6. In a typewriting machine, in combination, a carriage, means adapted to shift the carriage from initial position to a second position, a shift lever for actuating said means, pivoted means adapted to arrest the movement of said carriage when such position is reached, and a second shift lever adapted to 95 actuate said first-mentioned means to shift said carriage to a third position upon a movement of said arresting means in the direction of the movement of the carriage.

7. In a typewriting machine, in combination, a carriage, means adapted to shift the carriage from initial position to a second position, a shift lever for actuating said means, means pivoted to the frame of the machine adapted to arrest the movement of said carriage when such position is reached, a second shift lever adapted to 100 actuate said first-mentioned means to shift said carriage to a third position, and means actuated by said second shift lever adapted to permit a movement of said pivoted arresting means in the direction of the movement of the carriage, said last-mentioned means also operating to arrest the movement of said carriage in said third position.

8. In a typewriting machine, in combination, a carriage, movable arresting means, 125 and means for moving said carriage relatively to said arresting means to shift the same from initial position to a second position, the movement thereof being arrested by said first-mentioned means, said second-men- 130

- tioned means being adapted to move said carriage with said arresting means and substantially in the same direction to shift the carriage to a third position.
5. 9. In a typewriting machine, in combination, a carriage, pivoted arresting means, and means for moving said carriage relatively to said pivoted arresting means to shift the same from initial position to a second position, the movement thereof being arrested by said first-mentioned means, said second-mentioned means being adapted to move said carriage with said pivoted arresting means and in the same direction to shift the carriage to a third position.
10. 10. In a typewriting machine, in combination, a carriage, pivoted arresting means, means for moving said carriage relatively to said pivoted arresting means to shift the same from initial position to a second position, the movement thereof being arrested by said first-mentioned means, said second-mentioned means being adapted to move said carriage with said pivoted arresting means and in the same direction to shift the carriage to a third position, and means adapted to arrest the movement of said pivoted arresting means when the carriage has reached such third position.
15. 11. In a typewriting machine, in combination, a carriage, movable arresting means, means adapted to shift the carriage from initial position to a second position, a shift lever for actuating said means, said first-mentioned means being adapted to arrest said carriage when such position is reached, and a second shift lever adapted to actuate said first-mentioned means to move said carriage with said movable arresting means and in the same direction to shift the carriage to a third position.
20. 12. In a typewriting machine, in combination, a carriage, movable arresting means, means adapted to shift the carriage from initial position to a second position, a shift lever for actuating said means, said first-mentioned means being adapted to arrest the movement of said carriage when such position is reached, a second shift lever adapted to actuate said first-mentioned means to move said carriage with said movable arresting means to shift the same to a third position, and means actuated by said second shift lever adapted to permit a movement of said movable arresting means in the direction of the movement of the carriage.
25. 13. In a typewriting machine, in combination, a carriage, movable arresting means, means adapted to shift the carriage from initial position to a second position, a shift lever for actuating said means, said first-mentioned means being adapted to arrest the movement of said carriage when such position is reached, a second shift lever adapted to actuate said first-mentioned means to move said carriage with said movable arresting means and in the same direction to shift the carriage to a third position, and a cam actuated by said second shift lever adapted to permit a movement of said movable arresting means.
30. 14. In a typewriting machine, in combination, a carriage, movable arresting means, means adapted to shift the carriage from initial position to a second position, a shift lever for actuating said second-mentioned means, said first-mentioned means being adapted to arrest the movement of said carriage when such position is reached, a second shift lever adapted to actuate said first-mentioned means to move said carriage with said movable arresting means to shift the same to a third position, and a sliding cam actuated by said second shift lever adapted to permit a movement of said movable arresting means.
35. 15. In a typewriting machine, in combination, a carriage, movable arresting means, means adapted to shift the carriage from initial position to a second position, a shift lever for actuating said means, said first-mentioned means being adapted to arrest the movement of said carriage when such position is reached, a second shift lever adapted to actuate said second-mentioned means to move said carriage with said movable arresting means and in the same direction to shift the carriage to a third position, and a cam constantly engaging said arresting means adapted to be actuated by said second-mentioned shift lever to permit a movement of said movable arresting means and in the direction of the movement thereof.
40. 16. In a typewriting machine, in combination, a carriage, means for shifting the carriage from initial position to a second position, and cushioned means for arresting the movement of the carriage in such position, said cushioning arresting means being adapted to be moved to allow the carriage to be shifted to a third position.
45. 17. In a typewriting machine, in combination, a carriage, means adapted to shift the carriage from initial position to a second position, a shift lever for actuating said means, movable cushioning means adapted to arrest said carriage when such position is reached, a second shift lever adapted to actuate said first-mentioned means to shift said carriage to a third position upon a movement of said cushioning arresting means, and means actuated by said second shift lever adapted to permit a movement of said arresting means, said last-mentioned means operating to arrest the movement of said carriage in said third position.
50. 18. In a typewriting machine, in combination, a carriage, means adapted to shift the carriage from initial position to a second position, a shift lever for actuating said means, movable cushioning means adapted to ar-

rest the movement of said carriage when such position is reached, a second shift lever adapted to actuate said first-mentioned means to shift said carriage to a third position upon a movement of said cushioning arresting means, and a cam constantly engaging said arresting means and adapted to be actuated by said second-mentioned shift lever to permit a movement of said arresting means, said cam operating to arrest the movement of the carriage in said third position.

19. In a typewriting machine, in combination, a carriage, means for shifting the carriage from initial position to a second position, cushioning means pivoted to the frame of the machine adapted to silently arrest the movement of the carriage in such position, said first-mentioned means being adapted to shift the carriage to a third position upon a movement of said pivoted arresting means, and a cam constantly engaging said cushioning arresting means and adapted to be operated to permit a movement of said cushioning arresting means to allow the carriage to be shifted to said third position.

20. In a typewriting machine, in combination, a carriage, means adapted to shift the carriage from initial position to a second position, a shift lever for actuating said means, cushioning means pivoted to the frame of the machine adapted to silently arrest said carriage when such position is reached, a second shift lever adapted to actuate said first-mentioned means to shift the carriage to a third position, and a cam constantly engaging said cushioning means adapted to permit a movement of said pivoted arresting means, said last-mentioned means also operating to arrest the movement of said carriage in said third position.

21. In a typewriting machine, in combination, a carriage, movable cushioning arresting means, means for moving said carriage relatively to said first-mentioned means to shift the same from initial position to a second position, the movement thereof being arrested by said first-mentioned means, said second-mentioned means being adapted to move said carriage with said movable cushioning arresting means to shift the same to a third position, and a cam constantly engaging said arresting means adapted to silently arrest the movement thereof.

22. In a typewriting machine, in combination, a carriage, cushioning arresting means pivotally mounted in the frame of the machine, means for moving said carriage relatively to said cushioning arresting means to shift the same from initial position to a second position, the movement thereof being arrested by said first-mentioned means, said second-mentioned means being adapted to move said carriage with said first-mentioned arresting means to shift the same to a third

position, and a cam constantly engaging said first-mentioned means adapted to arrest the movement thereof when the carriage has reached the last-mentioned position.

23. In a typewriting machine, in combination, a carriage, means for shifting the carriage from initial position to a second position, means for arresting the movement of said carriage in such position, said arresting means being adapted to be moved in the direction of the movement of the carriage to allow the same to be shifted to a third position, means for returning the same to initial position, and a cushioned stop adapted to silently arrest the movement of said carriage when such initial position is reached.

24. In a typewriting machine, in combination, a carriage, means for shifting the carriage from initial position to a second position, movable means adapted to arrest the movement of the carriage in such position, said first-mentioned means being adapted to shift the carriage to a third position upon a movement of said movable arresting means in the direction of the movement of the carriage, means adapted to arrest the movement of said arresting means when the carriage has reached said last-mentioned position, means for returning the same to initial position, and a cushion adapted to silently arrest the movement thereof when said initial position is reached.

25. In a typewriting machine, in combination, a carriage, means adapted to shift the same from initial position to a second position, a shift lever for actuating said means, movable means adapted to arrest the movement of said carriage when such position is reached, a second shift lever adapted to actuate said first-mentioned means to shift said carriage to a third position upon a movement of said arresting means, means actuated by said second shift lever adapted to permit a movement of said arresting means in the direction of the movement of the carriage, said last-mentioned means operating to arrest the movement in said last-mentioned position, means for returning the carriage to initial position, and an air cushion adapted to silently arrest the movement of said carriage when the same has reached its initial position.

26. In a typewriting machine, in combination, a carriage, means adapted to shift the carriage from initial position to a second position, a shift lever for actuating said means, means pivoted to the frame of the machine and adapted to arrest the movement of said carriage when such position is reached, a second shift lever adapted to actuate said first-mentioned lever to shift said carriage to a third position, means actuated by said second shift lever adapted to permit a movement of said pivoted arresting means in the direction of the move-

ment of the carriage, said last-mentioned means also operating to arrest the movement of said carriage in said third position, means adapted to return the carriage to initial position, and an air cushion adapted to silently arrest the movement of said carriage when initial position is reached.

27. In a typewriting machine, in combination, a carriage, movable arresting means, means for moving said carriage relatively to said arresting means to shift the same from initial position to a second position, the movement thereof being arrested by said first-mentioned means, said second-mentioned means being adapted to move said carriage with said arresting means and in the direction of the movement thereof to shift the carriage to a third position, means for returning said carriage to initial position, and an air cushion adapted to silently arrest the movement of said carriage when initial position is reached.

28. In a typewriting machine, in combination, a carriage, movable cushioning arresting means, means for moving said carriage relatively to the first-mentioned means to shift the same from initial position to a second position, the movement thereof being arrested by said first-mentioned means, said second-mentioned means being adapted to move said carriage with said first-mentioned arresting means to shift the same to a third position, means adapted to return the carriage to initial position, and an air cushion adapted to silently arrest the movement thereof when said initial position has been reached.

29. In a typewriting machine, in combination, a carriage, movable cushioning arresting means, means adapted to shift the carriage from initial position to a second position, a shift lever for actuating said means, said first-mentioned means being adapted to arrest the movement of said carriage when the aforementioned position is reached, a second shift lever adapted to actuate said first-mentioned means to move said carriage with said movable cushioned arresting means to shift the same to a third position, a cam engaging said cushioned arresting means adapted to arrest the movement thereof when the carriage has reached the last-mentioned position, means for returning said carriage to initial position, and a cushioned stop connected with said carriage adapted to arrest the movement thereof when said initial position is reached.

30. In a typewriting machine, in combination, a carriage, a double rocker lever connected at one end with said carriage, a shift lever, means adapted to connect said rocker lever with said shift lever and adapted to be actuated thereby to shift said carriage from initial position to a second position, and cushioned means connected with said rocker lever adapted to arrest the movement of said

carriage when such position is reached, said arresting means being adapted to be moved in the direction of the movement of the carriage and to arrest the carriage when the same is shifted to a third position.

31. In a typewriting machine, in combination, a carriage, a double rocker lever connected at one end with said carriage, a shift lever, means adapted to connect said rocker lever with said shift lever and adapted to be actuated thereby to shift said carriage from initial position to a second position, cushioning means connected with said rocker lever adapted to arrest the movement of said carriage when such position is reached, said arresting means being adapted to be moved to shift the carriage to a third position, a second shift lever, and means adapted to be actuated thereby to permit a movement of said cushioning means to permit a movement of said carriage to a third position.

32. In a typewriting machine, in combination, a carriage, a double rocker lever pivoted to the frame of the machine and connected with the carriage, a shift lever, means connecting said rocker lever with said shift lever adapted to be actuated thereby to shift the carriage from initial position to another position, means adapted to be moved relatively to said carriage during the whole extent of its movement and with said carriage during a portion of its movement and adapted to silently arrest the movement thereof when such position is reached, a sliding cam connected with said shift lever having a constant engagement with said last-mentioned means and adapted to be moved thereby to permit a movement of the said last-mentioned moving means, means for returning said carriage to initial position, and an air cushion adapted to silently arrest the movement of said carriage when said initial position is reached.

33. In a typewriting machine, in combination, a carriage, a double rocker lever pivoted to the frame of the machine and connected with the carriage, a shift lever, means connecting said rocker lever with said shift lever adapted to be actuated thereby to shift the carriage from initial position to another position, means adapted to be moved relatively to said carriage during the whole extent of its movement and with said carriage during a portion of its movement and adapted to silently arrest the movement thereof when such position is reached, a sliding cam connected with said shift lever having a constant engagement with said last-mentioned means and adapted to be moved thereby to permit a movement of the said last-mentioned means, means for returning said carriage to initial position, and means connected with said rocker lever adapted to silently arrest the movement thereof.

34. In a typewriting machine, in combina-

tion, a carriage, a double rocker lever pivoted to the frame of the machine and connected with the carriage, a shift lever, means for connecting said rocker lever with said shift lever 5 adapted to be actuated thereby to shift the carriage from initial position to another position, means adapted to be moved relatively to said carriage during the whole extent of its movement and with said carriage during a 10 portion of its movement and adapted to silently arrest the movement thereof when such position is reached, means for returning said carriage to initial position, and an air cushion connected with said rocker lever 15 adapted to silently arrest the movement of said carriage.

35. In a typewriting machine, in combination, a reciprocating carriage, and an air cushion adapted to silently arrest the movement of said carriage from initial position to a second position, said air cushion being adapted to be moved to permit a movement of said carriage to a third position.

36. In a typewriting machine, in combination, a reciprocating carriage, an air cushion adapted to silently arrest the movement of said carriage from initial position to a second position, said air cushion being adapted to be moved to permit a movement of said carriage to a third position, and a sliding cam adapted to be operated to permit a movement of said air cushion.

37. In a typewriting machine, in combination, a reciprocating carriage, means connecting said carriage with a shift lever, and a movable air cushion, said carriage being adapted to be moved relatively thereto and also simultaneously moved therewith while being shifted from initial position to another 40 position, said air cushion being adapted to silently arrest said carriage when said position is reached.

38. In a typewriting machine, in combination, a reciprocating carriage, means connecting said carriage with a key lever, a movable air cushion, said carriage being adapted to be moved relatively thereto and also simultaneously moved therewith while being shifted from initial position to another position, said 50 air cushion being adapted to silently arrest said carriage when said position is reached, and a sliding cam also connected to said key lever and adapted to be operated thereby to permit a movement of said air cushion.

55. 39. In a typewriting machine, in combination, a reciprocating carriage, means connecting said carriage with a shift lever, a movable air cushion, said carriage being adapted to be moved simultaneously thereto and also 60 simultaneously moved therewith while being shifted from initial position to another position, said air cushion being adapted to silently arrest said carriage when said position is reached, a sliding cam also connected to said

silent lever and adapted to be operated thereby to permit a movement of said air cushion, means for returning said carriage to initial position, and an air cushion adapted to silently arrest the movement thereof when said initial position is reached. 65

40. In a typewriting machine, in combination, a carriage, a double rocker lever pivoted intermediate its length to the frame of the machine and connected at one end thereof with said carriage, a rock shaft, means connecting said rocker lever with said rock shaft, a forked rocker arm carried by said rocker shaft, a key lever shaft, a movable abutment mounted upon said last-mentioned shaft having a universal connection with said forked arm, a shift lever journaled upon said shaft and adapted to actuate said abutment, movable arresting means connected with the carriage, sliding means adapted to support said movable arresting means, and a connection 70 between said sliding means and said shift lever, said shift lever when actuated being adapted to shift said carriage and simultaneously to actuate said sliding means whereby the carriage is shifted from initial position to another position, said movable arresting means being provided with an air cushion to 75 silently arrest the movement of the carriage when such position is reached.

41. In a typewriting machine, in combination, a double rocker lever pivoted intermediate its length to the frame of the machine and connected at one end thereof with said carriage, a rock shaft, means connecting said rocker lever with said rock shaft, a forked 80 rocker arm carried by said rock shaft, a key lever shaft, a movable abutment having a lever journaled upon said shaft, a shift lever adapted to actuate said abutment, pivotally mounted arresting means, a cam roller journaled thereon, a sliding cam connected with 85 said shift lever, said shift lever being adapted when actuated to cause a movement of the carriage and simultaneously therewith a movement of said sliding cam whereby said pivoted arresting means is swung on its pivot to allow said carriage to be shifted from initial 90 position to another position, said pivoted arresting means being provided with an air cushion to silently arrest the movement of 95 said carriage when such position is reached, means for returning said carriage to initial position, and an air cushion adapted simultaneously to arrest the movement thereof.

42. In a typewriting machine, in combination, a shiftable carriage, a dash-pot, a piston working in said dash-pot and connected with the carriage, the engagement of the piston with the bottom of the dash-pot determining one shifted position of the carriage, a shift 100 lever connected with the carriage and adapted to shift the same, a reciprocal cam member upon which said dash-pot rests, and a 105

second shift lever connected with the carriage adapted to move the carriage to the second shifted position and simultaneously with such movement to withdraw the cam member from beneath the dash-pot during the latter shifting movement of the carriage.

In testimony whereof I affix my signature, in the presence of two witnesses.

WELLINGTON PARKER KIDDER.
